US00D847663S

(12) **United States Design Patent** (10) Patent No.: **US D847,663 S**
(45) Date of Patent: **** May 7, 2019**

(54) **WATCHCASE**

(71) Applicant: **CITIZEN WATCH CO., LTD.**,
Nishitokyo-shi, Tokyo (JP)

(72) Inventor: **Takuma Kohda**, Tokyo (JP)

(73) Assignee: **CITIZEN WATCH CO., LTD.** (JP)

(**) Term: **15 Years**

(21) Appl. No.: **29/638,596**

(22) Filed: **Feb. 28, 2018**

(51) LOC (11) Cl. **10-02**

(52) U.S. Cl.

USPC **D10/38**

(58) **Field of Classification Search**

USPC D10/30-32, 37-39, 122-124, 126, 128
See application file for complete search history.
